UNITED STATES PATENT OFFICE.

ROBERT WOOD JOHNSON, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

DESIGN FOR A TOOTHBRUSH.

Application filed April 21, 1927. Serial No. 21,658. Term of patent 14 years.

To all whom it may concern:

Be it known that I, ROBERT W. JOHNSON, a citizen of the United States, residing at New Brunswick, in the county of Middlesex and State of New Jersey, have invented a new, original, and ornamental Design for Toothbrushes, of which the following is a specification, reference being had to the accompanying drawing, forming part thereof.

Figure 1 is a side elevation of a toothbrush showing my new design.

Fig. 2 is a plan view of the same; and

Figure 3 is an end view of that end of the handle remote from the brush head.

I claim:

The ornamental design for a toothbrush, as shown.

ROBERT W. JOHNSON.
